UNITED STATES PATENT OFFICE.

JOHN CHISAN, OF LECKRONE, PENNSYLVANIA.

DESIGN FOR A BRUSH.

52,695.

Specification for Design.

Patented Nov. 19, 1918.

Application filed April 24, 1918. Serial No. 230,591. Term of patent 3½ years.

To all whom it may concern:

Be it known that I, JOHN CHISAN, a citizen of the United States, residing at Leckrone, in the county of Fayette and State of Pennsylvania, have invented a new, original, and ornamental Design for a Brush, of which the following is a specification, reference being had to the accompanying drawing, forming a part thereof.

The figure is a perspective view of a brush, showing my new design.

I claim:

The ornamental design for a brush, as shown.

JOHN CHISAN.

Witnesses:

JOHN HARRILLA, Jr.,
MIKE THORPACK.
